Patented July 12, 1966

205,220

COMPRESSION TAP CONNECTOR

John J. Klosin, 32 Colburn Road, East Brunswick, N.J.

Filed Mar. 15, 1965, Ser. No. 84,277

Term of patent 3½ years

(Cl. D26—1)

FIG. 1 is a perspective view of the front and left end of a compression tap connector showing my new design, in open condition;

FIG. 2 is a perspective view of the front and right end thereof; and

FIG. 3 is a cross-sectional view thereof in closed condition.

I claim:

The ornamental design for a compression tap connector, as shown.
